FULL-WIDTH WASHING MACHINES
 Hermann Verboom, Kempen, Germany, assignor to
 Eduard Kuesters, Krefeld, Germany
 Filed June 26, 1964, Ser. No. 378,375
 Claims priority, application Germany, June 29, 1963,

 1 Claim. (Cl. 68—181)

This invention relates to a full-width washing machine for webs of material, especially webs of fabric, in which a web of material is guided through the washing tank with loops running from the top to the bottom and the bottom to the top thereof and transverse walls are arranged on the bottom of the tank between the loops, the washing liquid entering the tank on the side on which the material passes out and leaves the tank on the side on which the material enters.

In the known full-width washing machines of the type above described, transverse walls are provided the height of which decreases from the side where the liquid enters to the side where it leaves the tank, so that the liquid flows through the tank in the form of a cascade. As the fabric web impedes the flow of liquid in the direction counter to its direction of travel, like a valve, the liquid can only flow through the tank at the side edges of the fabric web in counterflow thereto, whereas it is dammed up on the fabric web.

According to the invention the overflow forming the outlet for the liquid from the tank is arranged at a lower height than the upper edges of the transverse walls and a passage is formed at the bottom of the tank at alternate ends of the transverse walls.

The result is that, in forming the passages at the bottom of the tank, the washing liquid must flow transversely to the fabric web but nevertheless passes through the tank counter to the direction of travel of the fabric web, so that the washing liquid flushes the web in a continuous stream.

A passage can preferably be formed at the alternate ends of the transverse walls also at the upper edge thereof.

Some washing agents have a foaming effect, the foam being carrier of the dirt. This foam with the lighter particles of dirt must be guided upwards along the transverse walls. The invention also renders this possible.

The heavier particles of dirt sinking to the bottom are led off through the passages at the bottom of the tank.

The invention also allows passages to be formed simultaneously at the bottom of the tank and at the upper edge of the transverse walls, so that the invention enables all requirements to be met.

In order to form the passages, the ends of the transverse walls where the passages are to be formed are provided with extensions which are lower than the walls themselves and shiftable in vertical direction in relation thereto.

An embodiment of the invention is illustrated diagrammatically by way of example in the accompanying drawings, in which:

FIG. 1 shows a full-width washing machine in vertical section;

2

FIG. 2 is a top plan view of the bottom of the washing tank;

FIG. 3 shows the end of a side wall provided with a sliding extension, the slide being set for passage at the bottom, and

FIG. 4 is a similar view to FIG. 3 with the slide set for passage at the top.

The washing tank is designated by 1. The fabric is guided therein in loops running from the top to the bottom and from the bottom to the top. For this purpose rollers 3 are provided in the lower portion of the tank. The washing liquid is fed at 4. It flows off over the overflow 5. The web runs in at 6 and out at 7.

Transverse walls 8 are provided between the loops on the bottom of the tank.

15 The ends of the transverse walls are formed by a vertically shiftable slide 12 which is of lesser height than the transverse walls. By shifting the slides either a bottom passage 9 or a top passage 9' is produced. When the slide is in its intermediate position passages are formed both at the top and the bottom.

The overflow 5 is located at a lower level than the upper edge 10 of the transverse walls 8.

20 The resultant flow of washing liquid through the tank is indicated by the arrows 11.

25 What I claim is:

Full-width washing machine for webs of material comprising a tank, transverse vertical partitions extending partially across the width of the tank at the bottom thereof, each partition having its one end abutting one wall of the tank and its other end spaced at a predetermined distance from the opposite wall of the tank, each partition abutting the wall opposite the wall which the adjacent partition abuts, a vertical slidable panel element mounted adjacent to that end of each transverse partition spaced apart from the wall of the tank, said panel element of a width equal to the distance between the end of the partition and the wall of the tank, the height of each panel element being less than the height of the adjacent transverse partition, means for moving said panel elements vertically between a position in which the lower edge of each element is level with the lower edge of the adjacent transverse partition and a position in which the upper edge of the element is level with the upper edge of said transverse partition, means for moving the web to be washed through the tank from the entrance side to an exit side thereof along a path extending vertically into and out from chambers formed in the tank by the transverse partitions and slidable panel elements, an inlet for washing liquid adjacent the exit side of the tank and an outlet for said washing liquid adjacent the entrance side of the tank, said outlet being at a lower level than the upper edge of the transverse partitions.
